United States Patent Office.

WILLIAM FISHLEY SERJEANT, OF ST. LOUIS, MISSOURI.

Letters Patent No. 79,016, dated June 16, 1868; antedated June 4, 1868.

IMPROVED RAILROAD-RAIL TIE.

The Schedule referred to in these Letters Patent and making part of the same.

TO ALL WHOM IT MAY CONCERN:

Be it known that I, WILLIAM FISHLEY SERJEANT, of St. Louis, in the county of St. Louis, and State of Missouri, have invented a new and improved Method of Securing Down and Tying Together Railroad-Rails; and I do hereby declare that the following is a full, clear, and exact description thereof, reference being had to the accompanying drawings, making part of this specification, in which—

Figure 1 is a plan view of a portion of a railroad-track, showing my improved method of securing down and tying together the rails thereof.

Figure 2 is a side view of one side of the track.

Figure 3 is a cross-section of the track.

Similar letters of reference indicate corresponding parts in the several figures.

This invention relates to a new and improved method of securing down railroad-rails, whereby spikes, and other fastenings which are liable to become loose, are dispensed with, and the improved fastenings made to serve the several purposes of holding the rails down upon their wooden sleepers or cross-ties, preventing lateral displacement of the rails, and tying the rails of both sides of the track together in such manner as to prevent spreading or contraction thereof, all as will be hereinafter explained.

To enable others skilled in the art to understand my invention, I will describe one practical mode of carrying it into effect.

In the accompanying drawings, I have represented my invention applied to the well-known T-shaped rails; but it will be evident, from the following description, that, without changing the principle of the invention, it is applicable to railroads employing rails of other shapes.

The bed of the track may be made up of transverse ties, B B', arranged at suitable distances apart, and held down in the usual well-known manner. Upon these cross-ties I secure the rails by means of metal tie-bars or auxiliary ties, C C, which I prefer to make of the fish-belly form, shown in the drawings, fig. 3, as affording the greatest strength against vertical strain. The ends of these ties C terminate in hooks or jaws, a a, which are adapted for receiving the base flanges of the rails, and securing these rails firmly to the ties C.

The ties C are all made of an equal length, and slipped upon the rail-sections previously to securing these sections down in place, which is done by means of bolts, c b, passed through the cross-ties B B'. It will be seen that the metallic holding-down ties C serve as a most perfect means of gauging the rails in the act of laying them down, and, at the same time, preventing lateral spreading or contraction of the track.

The cross-beams B B' do not, in reality, serve the purpose of ties, as they are commonly employed, for they afford a means of securing in place the bars C, which serve as the ties; and they also serve, in conjunction with these ties C, as supports for the rails.

I do not confine myself to the exact shape of the ties C, nor to the shape of the jaws which grip or receive the bases of the rails, as other forms may be adopted which may be made to answer the same end.

If desirable, bolt or other fastenings may be applied very near the extremities of the ties C, as shown at c' c' in figs. 1 and 3; but, where the ties C possess sufficient strength and stiffness in themselves, two or three fastenings will answer every purpose.

I am aware that it is well known, in the construction of railroads, to employ tie-rods, having gripping-jaws on their extremities, for tying together the movable-switch sections of the track. In such instances, the tie-rods do not hold the rail-sections down upon the bed of the track.

I have above described my improved ties as applied to cross-beams, and secured thereto; but, if desirable, the ends of the ties may be recessed into longitudinal sleepers, and secured to them as well as to cross-beams between said sleepers.

I am aware that metal cross-ties have been employed with vertical recesses in their upper surfaces, near their ends, for receiving the base portions of rails, and preventing lateral movement of the rails upon their ties.

I am also aware that railroad-chairs have been connected together by cross-ties or tie-bars.

I am also aware that it is very common to employ cross-ties for movable-switch rails, which consist of jaws, embracing the base portions of the rails, connected together by tie-rods.

I do not, therefore, claim broadly a metal cross-tie, nor such as are shown in the Letters Patent of J. Winkley, October 23, 1866, John Elgar, March 12, 1845, and Eastman, September 3, 1867.

Having described my invention, what I claim as new, and desire to secure by Letters Patent, is—

1. The employment of a holding-down cross-tie, which is constructed with jaws upon its ends, which will embrace the rails, when said tie is secured to, or adapted for being secured to, the wooden bed of the track, by means substantially as described.

2. A metallic cross-tie, constructed of one piece of metal, with jaws, *a a*, upon its extremities, and with transverse perforations through it, as herein described and shown.

WILLIAM FISHLEY SERJEANT.
